UNITED STATES PATENT OFFICE.

WALTER P. BROWN, OF NEW HAVEN, CONNECTICUT, ASSIGNOR TO NEW HAVEN
KNITTING MILLS, INC., OF NEW HAVEN, CONNECTICUT.

DESIGN FOR HOSIERY.

Application filed December 16, 1924. Serial No. 11,716. Term of patent 7 years.

To all whom it may concern:

Be it known that I, WALTER P. BROWN, a citizen of the United States, residing at New Haven, in the county of New Haven and State of Connecticut, have invented a new, original, and ornamental Design for Hosiery, of which the following is a specification, reference being had to the accompanying drawing, forming part thereof.

The figure is a view in side elevation of a stocking showing my new design.

I claim:

The ornamental design for hosiery as shown.

WALTER P. BROWN.
